DESIGN FOR A BAIT BOX

Ray A. Gogarn, Detroit, Mich.

Application December 30, 1938, Serial No. 82,088

Term of patent 14 years

To all whom it may concern:

Be it known that I, Ray A. Gogarn, a citizen of the United States of America, residing at Detroit, in the county of Wayne and State of Michigan, have invented a new, original, and ornamental Design for a Bait Box, of which the following is a specification, reference being had to the accompanying drawing, forming part thereof.

Fig. 1 is a front elevation,

Fig. 2 is a rear elevation, and
Fig. 3 is a side elevation of a bait box, showing my new design.

I claim:

The ornamental design for a bait box, substantially as shown.

RAY A. GOGARN.
